DESIGN FOR A DAGGER OR THE LIKE

William E. Fairbairn, Washington, D. C., Fernleigh R. Graninger, Takoma Park, Md., and Earl G. Millison, Falls Church, Va.

Application October 13, 1944, Serial No. 115,751

Term of patent 7 years

(Cl. D22—6)

To all whom it may concern:

Be it known that we, William E. Fairbairn, a subject of the King of Great Britain, and Fernleigh R. Graninger and Earl G. Millison, citizens of the United States of America and residents of Washington, in the District of Columbia; Takoma Park, Maryland; and Falls Church, Virginia, respectively, have invented a new, original, and ornamental Design for Daggers or the like, of which the following is a specification, reference being had to the accompanying drawing, forming part thereof.

Fig. 1 is a side elevational view of a dagger or the like, showing our new design;

Fig. 2 is an end elevational view as seen from the hilt; and

Fig. 3 is an edge view thereof.

We claim:

The ornamental design for a dagger or the like, as shown.

WILLIAM E. FAIRBAIRN.
FERNLEIGH R. GRANINGER.
EARL G. MILLISON.
